UNITED STATES PATENT OFFICE.

CHARLES F. STODDARD, OF BOSTON, MASSACHUSETTS, ASSIGNOR TO AMERICAN PNEUMATIC SERVICE COMPANY, OF DOVER, DELAWARE, A CORPORATION OF DELAWARE.

CARRIER FOR PNEUMATIC-DESPATCH-TUBE APPARATUS.

No. 796,263.

Specification of Letters Patent.

Patented Aug. 1, 1905.

Application filed May 20, 1904. Serial No. 208,813.

To all whom it may concern:

Be it known that I, CHARLES F. STODDARD, of Boston, in the county of Suffolk and State of Massachusetts, have invented certain new and useful Improvements in Carriers for Pneumatic-Despatch-Tube Apparatus, of which the following is a specification.

My invention relates to new and useful improvements in carriers for pneumatic-despatch-tube apparatus, especially to such apparatus wherein large carriers are used for the transmission of mail-matter, merchandise, and the like.

The object of my invention is to make the cover of the carrier practically water-tight while the carrier is in transit.

My invention consists of certain novel features hereinafter described, and particularly pointed out in the claims.

In the accompanying drawings, which illustrate a construction embodying my invention, Figure 1 is a longitudinal section of the rear end of the carrier, the direction of travel being indicated by the arrow. Fig. 2 is a similar view showing a modification of the construction of the deflector-ring. Fig. 3 is an elevation of the upper part of the carrier.

Like letters of reference refer to like parts throughout the several views.

A represents the cover of the carrier, which is pivotally connected to the carrier-shell B at C. Just below the top of the shell is securely fastened the ring D, which flares out on the upper side, as shown, so as to overlap the flanged portion *a* of the cover A when said cover A is in its closed position, as shown in Fig. 1.

E represents a portion of the despatch-tube, and the large arrow F shows the direction in which the carrier travels. The small arrows *f* show the travel of any water which may be in the despatch-tube E relative to the motion of the carrier. It has been found that a cover of the style shown would pick up water in transit from the despatch-tube on account of the flanged portion *a* acting as a scoop. The water is deflected by the ring D away from the opening J between the flanged portion *a* of the cover A and the shell B. In Fig. 1 this deflector-ring D is shown separate from the ring G, the object of which is to hold the gasket-ring H, which is the sliding portion of the carrier.

In Fig. 2 a modification of Fig. 1 is shown in which A' represents the cover of the carrier, pivotally connected to the carrier-shell B' at C'. Below the top of the shell B' the ring D' is securely fastened, as shown, and flares out on the upper side so as to overlap the flanged portion *a'* of the cover A' when said cover A' is in its closed position, as shown in Fig. 2. In Fig. 2 the deflector-ring D' holds the gasket-ring H', which forms the sliding portion of the carrier. This modification differs from Fig. 1 only in that in Fig. 1 the ring G, which holds the gasket-ring H, is formed separate from the deflector-ring D, whereas in Fig. 2 the deflector-ring D' acts not only as a deflector-ring, but also holds the gasket-ring in place.

I do not limit myself to the arrangement and construction shown, as the same may be varied without departing from the spirit of my invention.

Any suitable locking mechanism for securing the cover A to the shell B of the carrier may be employed. None is here shown, as it forms no part of the present invention.

Having thus described the nature of my invention and set forth a construction embodying my invention, what I claim as new, and desire to secure by Letters Patent of the United States, is—

1. In a carrier for pneumatic-despatch-tube apparatus, a shell open at one end, a cover for closing said open end, and a deflector-ring secured to said shell and located adjacent to said open end for deflecting the water in the despatch-tube from said end.
2. In a carrier for pneumatic-despatch-tube apparatus, a shell open at one end, a cover for closing said open end and provided with a circular flange, and a deflector-ring secured to said shell and located around said flange when the cover is closed for deflecting the water in the despatch-tube from said end.

3. In a carrier for pneumatic-despatch-tube apparatus, a shell open at one end, a cover for closing said open end and provided with a circular flange which extends down over the shell when the cover is closed, and a deflector-ring secured to said shell and located around said flange when the cover is closed for deflecting the water in the despatch-tube from said end.

4. In a carrier for pneumatic-despatch-tube

apparatus, a shell, a cover for closing the interior of said shell, and means for deflecting the water in the despatch-tube from said cover.

5. A carrier for pneumatic-despatch-tube apparatus open at one end, a cover for closing said end, and means adjacent to said cover for deflecting the water in the despatch-tube from said cover.

In testimony whereof I have signed my name to this specification, in the presence of two subscribing witnesses, this 14th day of May, A. D. 1904.

CHARLES F. STODDARD.
